(57) **CLAIM**

We claim the ornamental design for a base trial component with stem adaptor, as shown and described.

DESCRIPTION

FIG. 1 is a top perspective view of a design of the base trial component with stem adaptor;

FIG. 2 is a first elevation view of the base trial component of FIG. 1;

FIG. 3 is a second elevation view opposite the first elevation view of FIG. 2;

FIG. 4 is a first side elevation view of the base trial component of FIG. 1;

FIG. 5 is a second side elevation view of the base trial component of FIG. 1;

FIG. 6 is a top plan view of the base trial component of FIG. 1;

FIG. 7 is a bottom plan view of the base trial component of FIG. 1; and,

FIG. 8 is a bottom perspective view of the base trial component of FIG. 1.

The features shown in broken lines depict environmental subject matter only and form no part of the claimed design.
